BAG

John H. Gordon, Birmingham, Mich.

Application January 11, 1932, Serial No. 585,920

5 Claims. (Cl. 206—12)

The invention relates to equipment bags and it has particular relation to a bag which is essentially adapted for use by physicians for carrying medicinal supplies, surgical instruments, and 5 other articles ordinarily carried by them in making professional calls.

Cognizance is taken of numerous bags that have been used by physicians for many years for carrying articles used in their profession. Insofar as known, however, the bags that ordinarily have been used have not had satisfactory facilities for accommodating the numerous and varied articles which must be taken along on professional calls, and in at least most instances, such 10 articles are haphazardly deposited in a rather ordinary type of bag. Moreover, in the bags that have been used, little attention has been given to locating and maintaining the various articles in a satisfactory and convenient arrangement 15 which would allow the physician to quickly select one or more articles to be utilized. In most cases such articles have been deposited in a bag sufficiently large to accommodate them, and then when the physician desired to remove some particular article, it was necessary to reach into the 20 bag and move the contents thereof around and separate them until the desired article was found. A bag which is so arranged that the articles are maintained in a definite and convenient order, 25 and which is so constructed that upon opening the bag the various articles are immediately placed in readily accessible locations, manifestly is quite advantageous from the physician's point of view. Moreover, a bag of this character prevents breakage and other damage which occasionally results from lack of order and arrangement of articles in the ordinary type of bag.

In addition to the above, it is quite important 30 that the physician's equipment be divided up in a manner more or less corresponding to the different types of cases involved in his profession. For example, in visiting one patient, certain types of surgical or other instruments may be used, in the case of another patient, medicine will only 35 be used, and in another case hypodermic injections may be called for. Having a bag which is designed so to separate the physician's equipment that he may have ready access to and be able to locate immediately the particular articles he desires to use, seemingly is of considerable 40 importance to the practicing physician.

It is one object of the invention to provide a 45 physician's bag which is so constructed and arranged that various articles constituting his equipment, will be located conveniently in the

bag, be separated so as to permit the physician to immediately obtain the article or articles wanted, and so arranged that breakage or damage of any part of the equipment will practically be eliminated.

Another object of the invention is to provide a bag of the above designated character, which can readily be opened to so place the various articles comprising the equipment in the bag, in readily accessible locations that the physician in making 10 his professional call, may immediately find the article or articles wanted without inspecting or hunting through the bag.

Another object of the invention is to provide a physician's bag which is extremely durable, which 15 is substantially tight for the purpose of preventing ingress of water, and which has a strongly professional appearance.

Another object of the invention is to provide a neat and compact bag which may be opened to 20 a wide degree, for the purpose of laying, so to speak, the entire equipment of the bag before the physician. Manifestly, it is quite convenient to the physician to have a bag which when opened, practically lays out the entire equipment therein before him so as to enable him to 25 practically see at a glance, everything in the bag so as to enable him to quickly select the articles wanted.

And in general it is an object of the invention 30 to provide a bag which will increase the efficiency of the physician's service, conserve his time, avoid mental aggravation resulting from inability to quickly find the articles wanted in the bag, or to deposit such articles in a convenient arrangement, and which will insure maintenance 35 of the articles in the bag in good condition at all times.

For an understanding of a particular form of 40 the invention, reference may be had to the accompanying drawings forming a part of the specification, wherein:

Fig. 1 is a perspective view illustrating a bag constructed according to one form of the invention;

Fig. 2 is a cross-sectional view taken substantially along the line 2—2 of Fig. 1;

Fig. 3 is a cross-sectional view on a larger scale, taken substantially along the line 3—3 of Fig. 1;

Fig. 4 is a detail view in cross section, particularly illustrating the manner in which the side compartments of the bag are hinged to the bottom compartment thereof;

Fig. 5 is a vertical cross-sectional view taken substantially along the line 5—5 of Fig. 2, par-

ticularly illustrating the manner in which certain articles comprising the physician's equipment, are arranged in one half of the bag;

Fig. 6 is a cross-sectional view taken substantially along the line 6—6 of Fig. 5;

Fig. 7 is a cross-sectional view on a larger scale, taken substantially along the line 7—7 of Fig. 6;

Fig. 8 is a cross sectional view on a larger scale, illustrating particularly the ampoule case shown by Fig. 6, and the manner in which the cover therefor may be latched in closed position;

Fig. 9 is a cross-sectional and perspective view, similar to that shown by Fig. 4, but illustrating a different form of means for hinging the compartments to the body of the bag.

Referring to Figs. 1 and 2 particularly, the bag illustrated comprises a base or body compartment 10, and pivotal upper side compartments 11 and 12. The side compartments 11 and 12 are adapted to be opened from opposite sides of the body compartment 10 as illustrated in broken lines in Fig. 2 and to hinge about opposite edge lines 13 and 14 of the latter. This opposed side-wise opening of the compartments 11 and 12 manifestly permits ready access to such compartments as well as to the body compartment 10 which is then exposed between the open side compartments. Handles 15 and 16, mounted on the compartments 11 and 12 adjacent their upper 30 and meeting edges when the bag is closed, are provided to carry the bag and a latch 17 fastened on the compartment 11 between the handles, and adapted to cooperate with a cooperative latch part on compartment 12 is employed for holding the compartments in their closed positions. This brief description indicates the general arrangement of the bag and the manner in which it is opened and closed.

Now, as shown particularly by Figs. 2 and 5, 40 the bottom compartment 10 of the bag, comprises a rectangular frame work 20 composed preferably of featherweight gumwood veneer, having side walls 21 and end walls 22. In constructing the frame work, the side walls may be glued to the end pieces or secured thereto in any other suitable manner. The bottom of the compartment preferably comprises a layer of pulpwood fibre indicated at 23, and this layer is glued or secured in any other suitable manner within 50 and to the lower edge portions of the frame work 20. From this description, it will be apparent that a substantially rigid box of rectangular construction is obtained which defines the outline of the compartment 10.

55 The lower surface of the bottom layer 23 is covered by a thin piece of leather 24, which preferably is glued to the bottom over the entire surface thereof to provide a fully unitary construction. On the inner surface of the side and end walls 21 and 22 of the frame work 20, a layer of fiber composition 25 is applied, this layer also being glued to the framework surfaces. The fiber composition 25 also may be applied to the upper surface of the bottom layer 23 if this is desired 60 and likewise glued to the upper surface thereof. The inner surfaces of the side and end walls of the framework 20, and the upper surface of the bottom are then covered by a thin layer of leather such as sheep skin skiver indicated at 26, this 65 layer of leather also being glued to the surfaces over which it is applied. Then the entire exterior surface of the frame work 20 is covered by relatively heavy leather 27, glued thereto to provide a substantial heavy leather covering for the bottom compartment 10. As shown particularly by

Figs. 1 and 3, side and end strips of leather 27 cover the sides and end walls, which meet at the corners of the compartment and are sewed together as indicated at 28. Consequently, when the stitching 28 is effected a substantially solid 5 leather covering for the compartment is provided. As shown best by Fig. 2, the leather covering 27 overlaps the bottom wall of the compartment to a point indicated at 30, and the overlapping leather portion preferably is positively 10 secured to the bottom by stitching indicated at 31 and this stitching extends entirely through the bottom wall. A plurality of bosses 31' in the form of rivets with rounded heads for example, may be located on the lower side of the bottom 15 to provide a support for the bag, and such rivets may be secured to the bottom of the compartment in any suitable manner such as by a riveting operation.

The compartments 11 and 12 are constructed 20 similarly and it is believed that the description of one compartment generally will be sufficient for both compartments. Referring to Figs. 2, 3 and 4, preferably the layers of fiber composition 25 extend upwardly at both sides of the bottom 25 compartment as indicated at 33 and are formed into arcuate shape as shown, to define the side and arcuate parts of the compartments. The bottom wall of each compartment as shown by Fig. 2, comprises a layer 34 of fiber composition 30 or the like, and the edge of this layer is glued preferably as indicated at 35 to the inner side surface of the fiber layer 33. The end walls of the compartment as shown particularly by Fig. 3, comprise layers of gumwood veneer or the like 35 indicated at 36, this layer fitting within the edges of the fiber layer 33 constituting the side wall of the compartment and being glued at its edges thereto. Preferably also the end wall 36 is provided with a fiber composition layer 37 which is 40 preferably glued to the inner surface of the gumwood layer. The inner surface of the compartment is covered by thin leather such as sheep skin skiver indicated at 38 and a similar layer 39 of leather may be employed to cover the lower surface of the bottom wall 34 of the compartment. To provide a hinging cover for the compartment, the thin layers of leather 38 and 39 may be extended beyond the free edge of the bottom layer 45 34 of the compartment, and between such layers of leather a layer of fiber composition 40 is provided to stiffen the cover. It will be noted that the fiber composition 40 and the layers of leather 38 and 39 at opposite sides thereof are deflected 50 in their closed position to substantially close the compartment. In this connection it is desired to call attention to the fact that the leather layers preferably are glued to opposed sides of the fiber composition so as to provide a unitary construction. To provide an abutment for the cover of 55 the compartment, a stiffening element 42 may extend along the inner side of the side wall 33 adjacent its free edge, and within the leather layer 38. The outer sides of the compartments and particularly the side walls thereof, are covered 60 by the side layer of relatively heavy leather 27 which extend upwardly around the side portions and such layers of leather similarly are glued to the fiber layers which they cover. The end walls of the compartment similarly are covered by heavy layers of leather indicated at 45 in Fig. 3 which are likewise glued to the gumwood veneer 36. Stitching as shown at 28 in Fig. 1, and Fig. 3 may be employed for connecting the meeting 65 edges of such outside leather layers.

It will be noted in the figures and particularly Figs. 5 and 6 that the bottom walls 34 of the compartments are disposed in vertically spaced relation with respect to the upper edges of the gum-wood veneer 21 in the bottom compartment and that the leather skiver in the bottom compartment is reversely folded as indicated at 48 to provide an annular space 49 around the upper edge of the bottom compartment to prevent ingress 10 of water thereinto. In this connection it may be stated that the layer of skiver on the inner surface of the bottom compartment may be integral with the layers of leather skiver 39 on the bottom walls of the compartments so as to provide unitary side leather layers in the bottom and side compartments. It is apparent that the end walls of the compartment and the side walls thereof extend around and project below the upper edge of the reversely folded leather portion 48 so that 20 should any water gain entrance between the edges of the bottom compartment and the upper compartments, such water would have to travel upwardly over the folded edge 48 before it could enter into the interior of the bag proper. Adjacent the reversely folded portion 48 of the leather skiver 26, and between the latter and the fiber composition 25, reinforcing fabric such as linen indicated at 50, may be employed to reinforce the construction at the hinging lines of the 30 compartments.

From the above description it should be apparent that the compartments 11 and 12 may be hinged into open and closed position substantially about the lines indicated at 13 and 14 and that the fiber layers 25 and the outside layers of leather 27 at such lines substantially constitute the hinging connections between the compartments 11 and 12 and the bottom compartment 10. This arrangement provides a neat exterior 40 appearance for the bag wherein the hinging connection is practically not noticeable.

For limiting opening movement of each compartment, an arcuate plate 55 having a slot 56, may be secured as indicated at 57 to that portion 45 of one end wall of each compartment projecting below the bottom wall 34 thereof, and such arcuate plate preferably is movable into a space provided for this purpose between the folded edge portion 48 of the skiver 26 and the fiber layers in 50 one end wall of the bottom compartment. It is of course manifest that any arrangement suitable for the purpose may be provided so long as the arcuate plates are free to move into and out of the end walls of the bottom compartment. Preferably, only one arcuate plate is provided for each 55 compartment and both plates on both compartments are located at the same end so that when the compartments are in their open position the plates will constitute obstacles only at one end of the bag. For limiting opening movement of the 60 compartments, pins or the like indicated at 58 extend through the slots 56 and are fixed to the end wall of the bottom compartment and such pins are adapted to engage the end of the slots at the 65 free ends of the arcuate plates 55 when the compartments are open. Various arrangements may be provided to limit the opening of the compartments but the arrangement described is found particularly suitable.

70 It has previously been stated that the folded edge portion of the skiver 26 provides a means for preventing ingress of water into the bottom compartment around the meeting edges of the side compartment and the bottom compartment. In 75 order to prevent ingress of water between the

meeting edges of the side compartments, the compartment 11 is shown as provided with a reinforcing lapping strip 60 which also is covered by the outside layer of leather 27 and this lapping strip 60 extends across the top of the bag and along 5 the opposite end walls thereof so that when the compartments are closed, it overlaps the meeting edges thereof. From this it follows that the bag is substantially leak proof and hence the contents thereof may be preserved in good condition. 10

Each of the handles 15 and 16 is pivotally connected to the compartment with which it is associated, by means of a metal ring 65 which at one end is pivotally connected to the compartment by means of a leather strip 66 reversely folded about 15 a portion of the ring and stitched to the leather layer 27, as indicated at 67 in Figs. 1 and 7. A smaller reinforcing strip 68 of leather or suitable reinforcing fabric may be looped about a portion of the ring 65 within the folded leather 66 and 20 likewise stitched by the stitching 67. An opposite portion of the ring 65 is pivotally associated with the handle proper in any suitable manner and the handle itself may be of any suitable and rigid construction. When both handles are 25 associated with the bag in this manner it is apparent that they can be brought into substantially abutting positions as shown by Fig. 1, and the bag is then carried readily by means supporting both compartments. 30

The cover for the compartment 11 preferably comprises two parts indicated at 70 and 71 in Fig. 5, which may be moved separately into open and closed positions, whereas the cover for the compartment 12 preferably constitutes a single 35 cover for the entire compartment. Any suitable means may be employed for latching each cover in closed position such as a hook 72 pivotally mounted on the cover which is adapted to engage an eye 73 secured to the reinforcing element 42 40 and projecting when the cover is closed through a slot in the latter. A leather lip 74 may be secured to each cover adjacent the hook 72 to facilitate opening the cover when the hook is unlatched. The compartment 12 with its single cover manifestly provides a long space which may be utilized for carrying various surgical instruments or other equipment that a physician uses, and which require a long space in the bag. It is apparent that 45 certain surgical instruments or other instruments 50 that the physician uses, of a particular character, may be located in this compartment so that the physician always knows where such instruments are located.

The covers 70 and 71 of the compartment 11, 55 however, cover separate compartments divided by a partition 76 shown by Fig. 5 or in other words the compartment 11 is divided into two smaller compartments individually closed by the covers 70 and 71. The smaller compartment at the left as 60 shown by Fig. 5 may be used for various articles of similar nature that the physician uses, but the other compartment shown at the right of Fig. 5 is particularly employed to receive ampoules. Hypodermic needles and the like may also be 65 stored in this compartment if this is found suitable, or if found more satisfactory they may be stored in the smaller compartment at the left of Fig. 5 so that the entire compartment 11 or the smaller compartment at the right may be devoted 70 to hypodermic injecting equipment.

As an ampoule carrier, a box 78 is fastened on the inner surface of the cover 71, and such box has a pivoted cover 79 which may be hinged to the box by an integral covering layer 79', or a 75

hinge of suitable character. The cover may be latched to the body of the box by latching means 80 comprising a yieldable metal element 81 having a bead 82 adapted to project into an opening 5 in the cover 79. When the cover is closed, it is apparent that the bead slips into the opening, whereas when the cover is to be opened, the bead slips out of the opening. In either case the latch will automatically operate so that it is only necessary to move the cover either into closed or open 10 position.

Within the box 78 a removable layer of sponge rubber 85 preferably is provided which has longitudinally spaced recesses 86 as shown by Fig. 6 15 adapted to receive the ampoule tubes 87. Similarly, the cover 79 is provided with a removable layer of sponge rubber or other suitable resilient and yielding material 89 also having recesses 90 complementary to the ampoule tubes. The fact 20 that the sponge rubber layers are removable facilitates cleaning them, and it is evident that the rubber readily may be washed and sterilized. Together the resilient layers in the box 78 and cover 79 provide a soft but positive locating means for 25 the ampoule tubes, thereby preventing breakage thereof while maintaining them in positively located positions.

It will be apparent from Fig. 6, that the compartment 11 may be opened by swinging it to the 30 right through an arc of substantially 90° and that the covers for the compartment will then be in a horizontal plane with the compartment at the right of the bottom compartment. The cover 71 may be opened by swinging it to the 35 left through an arc of substantially 180 degrees which will place the ampoule case 78 uppermost and substantially in a horizontal plane above the bottom compartment. Then the cover 79 for the ampoule case may be lifted by swinging it to the 40 right thus exposing the ampoule tubes in a readily accessible position.

For accommodating a thermometer resilient metal clips 93 and 94 are provided which, as best 45 shown by Fig. 2, have lip portions 93 adapted to clip the thermometer in place on one side wall of the bottom compartment. Preferably, the clips 93 and 94 are so located that they may in conjunction provide a support for a single thermometer or that they may be used separately 50 for this purpose. The clips preferably extend through openings in the leather skiver 26 and alongside the fiber composition 25 to the bottom wall of the compartment and may be riveted in place as indicated at 94 in Fig. 5.

It is desirable that various medicines be removable as a unit and for this purpose a bracket plate 95 shown by Fig. 5 is provided having a 55 base portion 96 which is adapted to support a group of bottles 97. The bottles are maintained in separated positions on the bracket 95 by means of a strap 98 extending through longitudinally spaced slots on the back wall of the bracket and which engage the outer surfaces of the bottles. When the bracket plate is in position the bottom 60 wall 96 thereof preferably seats on the bottom wall of the bottom compartment, with the back wall thereof against a side wall of the latter. When so positioned the bracket is adapted to be maintained in position by means of a latch 99, 65 preferably comprising a turnable eye 100 fastened to the side wall of the bottom compartment and which projects through a complementary slot in the back wall of the bracket. When the bracket 70 is in proper position, it is apparent that the eye 100 may be turned 90 degrees and across the slot

to lock the bracket plate against the side wall. The advantage of having a removable bracket plate is manifest because it permits the physician to remove the entire group of bottles as a unit and place them on a table or the like where all 5 of the bottles will be readily visible thereby enabling him to select the bottle or bottles desired without difficulty.

The advantages of the bag described seem obvious without detailed explanation other than 10 that already given. It is evident that the bag may be opened readily and that the side compartment can be placed in substantially horizontal planes at opposite sides of the bottom compartment thus permitting the physician to 15 see at a glance practically all that the bag contains, it being evident that he knows what the side compartments contain because ordinarily he will employ such side compartments only for 20 designated purposes. It is apparent that the bottom compartment will be readily visible as well as accessible, that the thermometer will readily be visible and releasable and so located that it is not apt to become broken, that the bottle supporting bracket can be readily removed, 25 and that other articles which may be deposited in the bottom of the bag can be readily seen at a glance. Moreover, it is apparent that the physician may immediately obtain access to the ampoule case and moreover that such ampoule 30 tubes will be maintained in good condition against breakage.

The bag provides a neat and compact construction, extremely durable, water tight in character, and very satisfactory for a physician's purpose in 35 making professional calls. The invention meets the most exacting requirements of physicians by providing a bag which maintains various articles comprising the physician's equipment in separated and readily accessible locations, which prevents 40 breakage of breakable articles, and which places practically the entire equipment before the physician when it is opened so that he can see at least in effect all of the articles therein at a glance. The arrangement of the component 45 parts of the bag eliminates haphazard depositing of articles therein that characterizes the ordinary bag used, and provides a construction which will be readily recognized by physicians as meeting a long felt need.

As an alternative manner of pivotally mounting the side compartments on the bottom compartment of the bag, a hinge may be employed instead of the solid leather outer member, as indicated at 101 and such hinge may constitute metal hinge 55 elements 102 and 103 fastened between the leather covering and bottom compartment and side compartments respectively, and through which a piano wire 104 or the like may extend. While 60 the leather covering outside of the bag is suitable for hinging purposes it may be found desirable to use metal hinge elements of this type.

Although certain forms of the invention have been shown and described in detail, it will be apparent to those skilled in the art that various 65 modifications may be made without departing from the scope of the appended claims.

I claim:

1. A physician's bag comprising a bottom compartment, a second compartment hinged to the 70 bottom compartment, a pivotal cover for the second compartment, an article case fastened on the inside surface of the cover, and a pivotal cover for the case, said case cover and said second compartment being pivoted to open in the same direc- 75

tion, and the second compartment cover being pivoted to open in the other direction.

2. A physician's bag comprising a bottom compartment including pairs of side and end walls, 5 a side compartment arranged above said bottom compartment, means for pivotally connecting said side compartment to the upper margin of a side wall of said bottom compartment, a cover for said side compartment, means for pivotally connecting 10 said cover at the bottom margin thereof to the bottom of the side compartment when the bag is in closed condition, and an ampoule case fixed to the inside surface of said cover and openable about an axis adjacent the bottom of the ampoule 15 case, whereby said ampoule case is disposed in a substantially erect position both when the bag is closed and when the bag, side compartment, and ampoule case are open.

3. A physician's bag comprising a bottom compartment including pairs of side and end walls, a 20 side compartment arranged above said bottom compartment, means for pivotally connecting said side compartment to the upper margin of a side wall of said bottom compartment, a cover for said 25 side compartment, means for pivotally connecting said cover at the bottom margin thereof to the bottom of the side compartment when the bag is in closed condition, an ampoule case fixed to the inside surface of said cover, and a cover for said 30 ampoule case pivotally connected at the bottom thereof to the bottom of the ampoule case and adjacent the pivotal connection between said side compartment and the cover therefor.

4. A physician's bag comprising a bottom rec- 35 tangular compartment, upper side compartments hinged to opposed sides of the bottom compartment respectively, and in their closed positions providing a closure to the bottom compartment with their side and end walls constituting upward

continuations of the side and end walls of the bottom compartment, each of said upper compartments in its closed position having a bottom wall overlying a part of the bottom compartment and a cover pivotally connected to the inner edge 5 of said bottom wall so that the pivotal covers for both side compartments extend upwardly between the latter, a relatively small article case fastened on the inner side of one of said pivotal covers and movable into and out of the adjacent side com- 10 partment upon hinging movement of the cover, and a cover hinged to the case and normally closing that side of the latter opposite the cover to which the case is fastened.

5. A physician's bag comprising a bottom rec- 15 tangular compartment, upper side compartments hinged to opposed sides of the bottom compartment respectively, and in their closed positions providing a closure to the bottom compartment with their side and end walls constituting upward 20 continuations of the side and end walls of the bottom compartment, each of said upper compartments in its closed position having a bottom wall overlying a part of the bottom compartment and a cover pivotally connected to the inner edge 25 of said bottom wall so that the pivotal covers for both side compartments extend upwardly between the latter, a relatively small article case fastened on the inner side of one of said pivotal covers and movable into and out of the adjacent side 30 compartment upon hinging movement of the cover, a cover hinged to the case and normally closing that side of the latter opposite the cover to which the case is fastened, and means in the 35 case for holding articles against movement during pivotal movement of the side compartment or the cover therefor.

JOHN H. GORDON.
